DESIGN FOR A LUGGAGE CATCH OR SIMILAR ARTICLE

Everett Worthington, deceased, late of Scarsdale, N. Y., by Lucile Worthington, Berkeley, Calif., administratrix, assignor to American Can Company, New York, N. Y., a corporation of New Jersey

Application August 8, 1939, Serial No. 86,532

Term of patent 7 years

To the Commissioner of Patents:

Be it known that I, Lucile Worthington, a citizen of the United States of America, residing in Berkeley, county of Contra Costa, and State of California, administratrix of the estate of Everett Worthington, deceased, late a citizen of the United States, and resident of Scarsdale, in the county of Westchester, and State of New York, whose post office address was 15 Oak Lane, Scarsdale, New York, here present the necessary papers relating to a new, original, and ornamental Design for a Luggage Catch or Similar Article, of which the following is a specification, reference being had to the accompanying draw-

ing, forming a part thereof.

Figure 1 is a perspective view of a luggage catch or similar article embodying the new design in open position; and

Figure 2 is a perspective view thereof in closed position.

The dominant features of my design reside in the portions shown in full lines.

I claim:

The ornamental design for a luggage catch or similar article, as shown and described.

LUCILE WORTHINGTON,
Administratrix of the Estate of Everett Worthington, Deceased.
